FOLDING COMB

Murry Abbott, North Providence, R.I., assignor to
Cornell Manufacturing Co., Woonsocket, R.I.

Filed Nov. 17, 1971, Ser. No. 199,820

Term of patent 14 years

Int. Cl. D28—03

U.S. Cl. D86—8

FIG. 1

FIG. 2

FIG. 3

FIG. 4

FIG. 6

FIG. 5

FIG. 7

FIG. 8

FIG. 1 is a front elevational view of a folding comb showing my new design;

FIG. 2 is an end view, looking from the right with respect to FIG. 1;

FIG. 3 is an end view, looking from the left with respect to FIG. 1;

FIG. 4 is a bottom plan view thereof;

FIG. 5 is a top plan view thereof;

FIG. 6 is a section taken on line 6—6 of FIG. 1;

FIG. 7 is a front elevational view showing the comb in partially open position; and

FIG. 8 is a front elevational view showing the comb in completely open position.

I claim:

The ornamental design for a folding comb, substantially as shown.
